DESIGN FOR A STOVE.

Design No. 12,603, dated December 20, 1881.

Cut 270.

UNITED STATES PATENT OFFICE.

H. CLAY BASCOM, OF TROY, AND TOBIAS S. HEISTER, OF LANSINGBURG,
ASSIGNORS TO N. S. VEDDER PATTERN WORKS, BASCOM, GALBRAITH
& CO., OF TROY, NEW YORK.

DESIGN FOR A STOVE.

SPECIFICATION forming part of Design No. 12,603, dated December 20, 1881.

Application filed November 19, 1881. Term of patent 7 years.

To all whom it may concern:

Be it known that we, H. CLAY BASCOM, a citizen of the United States, residing in the city of Troy, in the county of Rensselaer and State of New York, and TOBIAS S. HEISTER, a citizen of the United States, residing in the village of Lansingburg, in said county and State, have jointly invented and produced a new and original Design for a Stove, of which the following is a specification, reference being had to the accompanying cut, print, or engraving of a stove which embodies said new design.

The design for the hooded urn A is not a part of this invention.

The design for the urn base B consists of the concave upper molding, a, having the connected series of peculiar ornamentations a', in combination with the lower convex molding, b, having thereon the series of semicircular arches b' bordered inside by scallop edgings, and the series of three-leaf ornaments c under each arch, and all shaped and arranged substantially as represented in the aforesaid print.

The design for the upper front panel, C, consists of the oblong rectangular block-form part d, having parallel sides and the semicircular projections e at the ends, the name-tablet f extending diagonally across the part d and having the inturned angular end parts, f', the diagonally-opposite radial corner ornaments, g, and the incut plant-form ornament h, partly covered by said name-tablet, all shaped and combined substantially as shown in the accompanying engraving.

The design for the lower front panel, D, consists of the representation of a boat, i, with upcurved ends on wavy water j, two human figures k l, seated face to face in the boat, one holding a harp and both covered by an overspread sail or awning, m, and all surrounded by a border, n, and the whole shaped and com-

bined so as to present substantially the appearance represented in the accompanying cut.

The design for the end panel, E, consists of the representation of a crested human figure, 45 o, in female attire, and standing on plant-clothed ground p, and holding a shield, q, the same having a border, r, and all shaped and arranged so as to present substantially the appearance shown in the aforesaid print. 50

The design for the legs consists of the representation of a growing inclined palm-tree, t, with foreground and background u bordered by a circle, v, open at the top and having laterally-extending upper ornamental parts, w x, 55 all shaped and combined on the convex upper portion of the leg so as to appear substantially as represented in the accompanying engraving.

What we claim as our joint invention is—

1. The design for the urn-base B, composed 60 of the parts a a' and b b' c, all shaped and arranged together as shown and described.

2. The design for the upper front panel, C, consisting of the parts d e f f' g h, all shaped and combined as set forth. 65

3. The design for the lower front panel, D, composed of the parts i j k l m n, all shaped and arranged as described.

4. The design for the end panel, E, composed of the parts o p q r, all shaped and arranged as described. 70

5. The design for the legs, composed of the parts t u v w x, all shaped and arranged as described.

In testimony whereof we hereunto set our 75 hands, in the presence of two subscribing witnesses, this 17th day of November, 1881.

H. CLAY BASCOM.
TOBIAS S. HEISTER.

Witnesses:

AUSTIN F. PARK,
JAMES T. GOODFELLOW.
